UNITED STATES PATENT OFFICE.

LOUIS D. GREGG, OF HACKENSACK, NEW JERSEY, ASSIGNOR TO THE GREGG COMPANY LTD., OF HACKENSACK, NEW JERSEY.

RAILWAY JOURNAL BOX.

Application filed May 12, 1927. Serial No. 190,734.

This invention relates to an improvement in the construction of journal boxes for railway bearings and the like. There are large quantities of these boxes in use of standard size in both outer and inner dimensions so as to fit the standard mountings for the same now in use and to receive the standard axles. Neither the inner nor outer size of the journal boxes can be changed because of the necessity for meeting these existing standards.

Considerable difficulty has, however, been experienced with the present form of journal box because of the narrowness of the ledges which support the journal bearing or "brasses", permitting the brasses slipping off the ledge and getting out of position with consequent damage to the various parts.

It is an object of the present invention to overcome this difficulty by providing in the journal boxes wider supports or ledges for the journal bearings or brasses without, however, preventing the use of such improved boxes with standard car axles and box mountings.

A more specific object of the invention is to provide a journal box of the type described, having instead of the usual narrow continuous ledge, a series of wider lugs or projections which on opposite sides of the box are staggered, the lugs on one side being opposite the space between the lugs on the opposite side, providing a wide support on which the journal brass may rest and permitting the standard collared car axle to be passed in a zig-zag manner between said lugs.

Another object of the invention is to provide a journal box of the type described which will permit more efficient lubrication of the bearings.

Various other objects and advantages will appear as the description of the invention proceeds.

In the accompanying drawings which illustrate a preferred form of embodiment of the invention:

Figure 1 shows a sectional plan view of one form of journal box with a journal member or axle partly inserted therein; the said axle member being outlined in dot and dash.

Fig. 2 shows a front view of the journal

box partly in section on the line 2-2 of 55 Figure 1.

Fig. 3 shows a sectional view on the line 3-3 of Figure 1.

Fig. 4 shows a perspective view of a "brass" or journal bearing of the type used 60 in the box as shown.

In the embodiment of the invention illustrated in Figure 1 of the drawings, a journal box 10 is provided with ledges 11 and 12 projecting out from the side walls thereof 65 in position to support the brasses; these ledges are provided with extended portions or lugs 13-14 and 15 as illustrated and portions of lesser width as shown at 16 and 17. The arrangement of these ledges or lugs is 70 such that each wide portion is opposed to a narrow portion in the opposite member, and the spacing is such as to permit the collar 22 on the axle 21 to move in a zig-zag manner past each lug. 75

The axle 21 with collar 22 is shown partially inserted in the box 10 of Figure 1. It will be seen that while the collar 22 might not pass the ledge members 13, 14 and 15, if the sides thereof were in straight line, it is 80 possible with the ledges in the form shown by applying a rocking, or weaving motion to the journal to move the collar alternately into and out of the narrow spaces between the ledges and to enable it to pass the wider 85 parts thereof.

It will be understood that once the collar 22 has passed all the lugs 13, 14 and 15, the axle may assume its true relation to the bearings with the collar 22 inside the inner lugs 90 and the lugs extending inwardly beyond the edge of the collar but not into contact with the axle portion 21.

In the assembled bearing as illustrated in Fig. 2 the edges 18 and 19 of the brass 20 95 rest upon the lugs 13, 14 and 15 and the brass in turn rests upon the axle 21, the weight of the car resting on the top of the journal box.

The extra width of the ledges 11 and 12 100 due to the projection of the lugs 13, 14 and 15 effectively prevent the brass 20 from slipping off the ledges as often happened with prior boxes, and the spaces 16 and 17 between the lugs, permits the lubricant which is packed in the bottom of the box to work up under the brass and then down over the journal providing better lubrication than 105

where the edges of the brass rests on a continuous ledge.

In assembling the journal box on an axle the axle is usually the stationary member and the journal box is weaved back and forth over the collar of the axle to cause the lugs to pass the collar.

It will be understood that the size and shape of the lugs 13, 14, 15, etc., may be varied, that the collar 22 need not always be wider than the distance between the lugs 13, 14 and 15 and that various other modifications and changes may be made in the embodiments of my invention illustrated without departing from the spirit of the invention or the scope of the appended claims, which are intended to cover the provision of wider brass ledges without interfering with the use of my journal box with standard 20 housings and axles.

Having thus described my invention, what I claim as new and desire to secure by Letters Patent is as follows:

1. In a journal box of the class described, ledges extending along the inner walls thereof, the said ledges being of irregular width and so placed that the wide portions on one will be opposite to narrow portions of the other.
2. In a journal box of the class described, opposite ledges within the walls of the said box of such form that alternating wide and narrow portions thereof will be in the position that each wide portion of one ledge is opposite to a narrow portion of the opposing ledge throughout the length of the said ledge members.
3. In a journal box of the class described, internal, longitudinal side ledges having alternate recesses and projections therein and so placed that the projecting portions of each are opposite to the receding portions of the other.
4. In a journal box of the class described, spaced projections on the opposite inner side walls of said box in position to support a brass bearing from falling therebetween, the projections on one side being opposite spaces on the opposite side wall.
5. In a journal box of the class described for use with an axle having a collar thereon, staggered spaced projections on the opposite inner side walls of said box in position to support a brass bearing from falling therebetween, the space between the free edges of all the projections on each side being less than the diameter of the axle collar, and the distance between the edge of any projection of one side for a distance equal to the thickness of the axle collar to the edge of the

projection on the other side being greater than the axle collar diameter.

6. In a journal box of the class described, equipped with fittings of conventional pattern, and longitudinal shelf-like members on the inner side walls thereof projecting inwardly beyond the journal collar, the said members being adapted to serve as retainers for a "brass" bearing members, and being so formed that their inner edge portions present an irregular alignment of such contour as to require the passing of the collar of a journal member with a weaving movement when same is inserted.

7. In a journal box of the class described adapted to receive a collared shaft, longitudinal ledge members located on the inner side walls thereof, the said ledge members having flat top surfaces adapted to support a brass bearing member, and their inner side portions formed with alternating projections and receding portions, the said projections and receding portions so disposed that the base surfaces of the receding portions are in line with the others of the same ledge, and the surfaces of the projecting portions are in similar alignment, the distance between the projecting portions being less than the diameter of the shaft collar.

8. In a journal box of the class described, a casing, shelf-like longitudinal projecting members within the said casing, extending inwardly beyond the axle collar, the inner portions of the said shelf-like members presenting a broken alignment in which the narrow portions of each are opposed to, and of opposite contour to the wide portions of the opposing member.

9. In a journal box of the class described an inwardly projecting ledge on each side thereof in position to support a brass bearing from falling therebetween and wider than the standard ledges of said boxes, and means to permit the journal box to be assembled on an axle having a collar of greater diameter than the distance between said ledges comprising cut-away portions in staggered relation.

10. In a journal box of the class described, internally projecting means extending into the center of said box and adapted to form ledges for supporting brasses, the effective interior extension of said means leaving a less space than that required for a collared axle and means to insert a collared axle therein.

In testimony whereof I have affixed my signature to this specification.

LOUIS D. GREGG.
